DESIGN FOR A FRESNEL LENS OR SIMILAR ARTICLE.

Emilio Pascucci, Corning, N. Y., assignor to
Corning Glass Works, Corning, N. Y., a cor-
poration of New York

Application October 13, 1939, Serial No. 87,653

Term of patent 14 years

To all whom it may concern:

Be it known that I, Emilio Pascucci, a citizen
of the United States of America, residing at Corning,
county of Steuben, and State of New York,
have invented a new, original, and ornamental
Design for a Fresnel Lens or Similar Article,
of which the following is a specification, refer-
ence being had to the accompanying drawing,
forming part thereof.

The figure is a side elevational view of a fresnel
lens or similar article showing my new design.

I claim:

The ornamental design for a fresnel lens or
similar article, as shown.

EMILIO PASCUCCI.
